JOHN T. ALLMAND AND JOHN D. LAWRENCE, OF DETROIT, MICHIGAN, ASSIGNEES TO
TERNSTEDT MANUFACTURING CO., OF DETROIT, MICHIGAN, A CORPORATION OF
MICHIGAN.

COUNTERBALANCING-SPRING FOR WINDOW-LIFTERS.

1,278,554.

Specification of Letters Patent. Patented Sept. 10, 1918.

Application filed February 5, 1918. Serial No. 215,437.

To all whom it may concern:

Be it known that we, JOHN T. ALLMAND and JOHN D. LAWRENCE, citizens of the United States, residing at Detroit, in the county of Wayne and State of Michigan, have invented a new and useful Improvement in Counterbalancing-Springs for Window-Lifters, of which the following is a specification.

10 This invention relates to counter-balancing springs for window lifts used in closed automobile bodies. Window lifts operated by a crank are now in quite general use for raising, lowering and locking the window in 15 various positions, and most of them now in use operate on the principle of a continuous chain which is rotated first in one direction and then in the opposite direction a sufficient distance to raise or lower the window. Like 20 any hoist, it is easier to lower the object than to raise it unless some counter-balancing means is provided. It is now quite common to employ a counter-balancing spring.

It is the object of the present invention to 25 improve the operation, endurance and assembling of this counter-balancing spring in the manner now to be described.

In the drawings,—
Figure 1 is a side elevation of the top of 30 the window lift viewed from the inside and with the cover plate removed.

Fig. 2 is an edge view of this apparatus.
Fig. 3 is a view of the counter-balancing spring and the cup which contains it.

35 Fig. 4 is a section of the same on the line A—A of Fig. 3.

Fig. 5 is an elevation of the stamped driven gear.

Fig. 6 is a detail sectional view showing 40 the connection of the spring and barrel.

a designates a plate upon which the operating devices of the window lift are assembled. b is the driven gear; c the driving pinion; d a pawl operating in connection 45 with a stop which serves to lock the window in various positions but which need not here be illustrated. e is the chain which carries a pin f for lowering and raising the window (which is not shown). The driven gear is a 50 stamping cupped as shown in Fig. 4 so it is adapted to contain the coiled counter-balancing spring g.

The counter-balancing spring would have to lie between the cupped portion of the

driven gear b and the plate and its coils 55 would be free to move laterally out of the assigned position giving certain portions of the spring a twisting or torsional strain. This has resulted in the breaking of a good many springs. It also results in a metallic 60 sound or noise when any one of the coils of the spiral leaves its proper position and strikes against the side of the plate.

These objections are avoided by providing a cup h centrally cut away at i so as to 65 allow the protrusion of the pin j into the spring housing. This pin j is fast to the plate a. Not only does the spring retaining cup serve to prevent this lateral movement of the spring causing both noise and torsional strains, but it serves as a very convenient way to assemble the spring and remove it.

The spring ordinarily would tend to assume a coil whose outer diameter is greater 75 than the diameter of the cup. Consequently the spring has to be packed into the cup by pressure, as crowding it in with a block and hammer. The outside end of the spring is riveted to the cup periphery at k. The inside of the spring has a loop. The spring is conveniently held in this cup, which keeps the coil from falling apart. The loop can be dropped over the pin j and the cup crowded into the cup portion of the driven gear, 85 which is nicely calculated to fit so that the two will rotate together. This arrangement, therefore, permanently fastens the outer end of the spring to the rotating member and the inner end of the spring to the stationary 90 member so that the chain in lowering the window will wind up the spring into a smaller coil and put it under tension to store energy for the lifting movement.

What we claim is:

1. In a window lift, the combination of a cupped driven member, a stationary plate adjacent said driven member, a cup provided with a central aperture, a member projecting from said stationary plate through said central aperture, the said cup being removably fitted into the cupped driven member so that the two rotate together, and a coiled counter-balancing spring packed into the cup with the outer end fastened to said cup 100 and the inner end securably to the member projecting from said stationary plate.
2. In a window lift, the combination of a

cupped sprocket wheel, a stationary plate provided with a pin projecting into the interior of the said cupped sprocket; a cup removably fitted into the cupped sprocket to rotate therewith and provided with a large central aperture to clear said pin, and a spring packed in said cup and having its outer end fastened thereto and its inner end adapted to fit over the said pin.

In witness whereof we have hereunto set our hands on the 2nd day of February, 1918.

JOHN T. ALLMAND.
JOHN D. LAWRENCE.
